WORK-CLAMPING MEANS

Ernest Casavant, New York, N. Y., and Harry E. Osborne, Shillington, and Harry L. Meek, Lincoln, Pa., assignors to United Shoe Machinery Corporation, Flemington, N. J., a corporation of New Jersey

Application August 20, 1942, Serial No. 455,456

5 Claims. (Cl. 12—14.1)

This invention relates to work-clamping means for lasting machines and is herein illustrated as applied to a lasting machine of the type illustrated in United States Letters Patent No. 2,045,595, granted June 30, 1936 on an application filed in the names of A. E. C. Hall et al.

In lasting certain types of shoes such, for example, as shoes of the prewelt type, it is particularly desirable that the shoe be accurately located in a predetermined lengthwise position in the lasting machine in order to insure a high degree of uniformity in the operation of the lasting wipers. In order to achieve this result, prewelt lasting machines have been provided with an end-embracing band having a rigid central member which serves to locate the band positively on its supporting member and also provides a positive means for positioning the shoe lengthwise thereof relatively to the lasting wipers. Such an end-embracing band is illustrated in an application for United States Letters Patent Serial No. 451,889 filed July 22, 1942 in the name of Andrew Eppler, Jr.

It is an object of the present invention to provide an end-embracing band for such a machine in which there will be no sharp division line between the area acted on by the rigid central member and the adjacent areas acted on by the backing member of the heel band, which, as illustrated in the application above referred to, is a yielding resilient metal band or plate.

With the above object in view, the present invention provides, in an end-embracing band for lasting machines having a rigid central member, a yielding backing member, and a work-engaging member carried by said backing member, a pressure-equalizing member positioned between the work-engaging member on the one hand and said rigid central member and said backing member on the other hand. As herein illustrated, said pressure-equalizing member is a resilient plate the side portions of which are positioned between the upper portion of said work-engaging member and resilient fingers forming the upper portion of the backing plate.

The invention will now be described with reference to the accompanying drawing illustrating the preferred embodiment thereof and pointed out in the appended claims.

In the drawing,

Fig. 1 is a perspective view of a heel band embodying the features of the present invention;

Fig. 2 is a perspective view similar to Fig. 1, with a portion of the backing plate broken away to show the pressure-equalizing member;

Fig. 3 is a sectional view illustrating the band shown in Fig. 1 in conjunction with parts of a lasting machine, such as that illustrated in the Eppler application hereinbefore referred to, and the rear portion of a prewelt upper on a last; and

Fig. 4 is an enlarged fragmental view taken in section on the line IV—IV of Fig. 1.

The illustrated heel band in its general construction is substantially the same as one form of heel band illustrated and described in the Eppler application above referred to. As illustrated in Fig. 1, the heel band comprises an upper-engaging member or lining 10 which is preferably made of grain leather with the grain face exposed and a backing member 12 of resilient metal, the end portions of which are secured to the end portions of the lining by rivets 14. The upper portion of the plate 12 has formed thereon a plurality of upwardly extending fingers 16 which are curved inwardly to insure the engagement of the upper portion of the band with that portion of the upper adjacent to its overlasting margin. Secured to the central portion of the plate 12 is a rigid member comprising a plate 18 the upper-facing surface of which has a curvature heightwise of the upper complementary to the curvature of the backseam portion of the upper and a plate 20 secured to the plate 18, said plate 20 being dove-tailed in cross section to provide a locking connection to a heel band supporting crosshead 22 (Fig. 3). The upper portion of the plate 12 adjacent to the rigid member 18 is cut away so that the resilient fingers 16 do not extend around the central portion of the band but terminate at opposite sides of the rigid member 18, and the upper portion of said member 18 occupies the same position relatively to the lining member 10 at the central portion of the heel band as the fingers 16 occupy along the side portions of said band.

By reason of the fact that the member 18 is rigid while the adjacent fingers 16 are resilient, there is a tendency for the central portion of the band adjacent to the rigid member 18 to press harder against the upper than the adjacent side portions of the band, leaving an impression in the back-seam portion of the upper which would be visible in the finished shoe. In order to equalize the pressure of the central portion and adjacent side portions of the band against the shoe upper, and thus to avoid the formation of an impression in the upper by the operation of the band, the illustrated band is provided with a relatively narrow resilient plate 24 (Fig. 2) which is sub-

stantially thinner than the plate 12 and sufficiently flexible so that it does not seriously interfere with the operation of the fingers 16, but is still sufficiently rigid to prevent the pressure of the rigid member 18 from being localized upon a clearly defined area of the back-seam portion of the upper. As illustrated in Fig. 1, the plate 24 lies between the fingers 16 and the outer surface of the lining member 10 with its upper edge adjacent to the upper edge face of said lining member. While the plate 24 may be riveted or otherwise securely fastened to the lining member or to the rigid member 18, if so desired, it seems preferable to mount the plate freely between the lining member and the backing member 12 without restricting it in any way by securing it to any part of the heel band. In the operation of the heel band, the plate 24 will be impressed into the outer surface of the lining member 10, as shown in Fig. 4, thus forming a shallow recess in the lining member within which the plate 24 will normally be retained by the fingers 16 without danger of dislocation.

Having thus described our invention, what we claim as new and desire to secure by Letters Patent of the United States is:

1. In a lasting machine, an end-embracing band comprising a rigid central member, a yielding backing member carried by said central member, a work-engaging member carried by said backing member, and a pressure-equalizing member positioned between the work-engaging member on the one hand and said rigid central member and said yielding backing member on the other hand.

2. In a lasting machine, an end-embracing band comprising a rigid central member, a flexible backing member carried by said rigid central member, said backing member including a plurality of upwardly extending resilient fingers, a work-engaging member carried by said backing member, and a resilient plate positioned between the work-engaging member on the one hand and

said rigid central member and the fingers of said backing member on the other hand for equalizing the pressure of the band against the shoe.

5. 3. In a lasting machine, an end-embracing band comprising a rigid central member, a yielding backing member carried by said central member, a work-engaging member carried by said backing member, and a pressure-equalizing member freely mounted between the work-engaging member on the one hand and said rigid central member and said yielding backing member on the other hand.

15. 4. In a lasting machine, an end-embracing band comprising a rigid central member, a flexible backing member carried by said rigid central member said backing member having a plurality of upwardly extending resilient fingers, a work-engaging member, and a resilient plate one surface of which is in contact with the work-engaging member while its opposite surface is in contact with said rigid central member and said fingers.

20. 5. In a lasting machine, an end-embracing band comprising a rigid central member, a backing member carried by said rigid central member and arranged to extend from said central member about opposite sides of an end portion of a shoe, said backing member having a plurality of upwardly extending resilient fingers certain of which are adjacent to said rigid central member, and a resilient plate interposed between the work-engaging member and the other parts of the band, the inner surface of said plate being in contact with the work-engaging member while its outer surface is in contact with the rigid central member and with said resilient fingers adjacent to and at opposite sides of said central member.
